15 Joseph B. Feder,
BY Everett Brook, ATTORNEYS.

UNITED STATES PATENT OFFICE.

JOSEPH B. FEDER, OF EAST ORANGE, NEW JERSEY.

ELECTRIC HEATER FOR RAILWAY SWITCHES.

Application filed December 8, 1920. Serial No. 429,068.

To all whom it may concern:

Be it known that I, JOSEPH B. FEDER, a citizen of the United States, and a resident of East Orange, in the county of Essex and State of New Jersey, have invented new and useful Improvements in Electric Heaters for Railway Switches, of which the following is a specification.

This invention relates in general to railway track switches and more particularly to improved heating means for such switches for melting snow and ice at and in the vicinity of the switch points to ensure proper operation thereof in cold weather.

The objects of the invention are to provide improved means for electrically heating the switch points to maintain them clear of snow and ice; to provide improved electric heating elements directly in the slide plates of the switch points which may be controlled from a point distant from the switch and which will constantly maintain the slide plates and switch points at a sufficient temperature to melt the snow and ice thereabout; to provide a slide plate for railway track switches having an electric heating element removably mounted therein; to provide an electrically heated slide plate embodying novel features of construction including a main plate and a top or bearing plate to support a switch point, and an electric heating coil embodied directly therein between said main plate and top or bearing plate; to provide such a construction which will withstand the shocks incident to the use of railway switches and which is weather-proof; to provide an improved electric heating coil particularly adapted for application to railway switch slide plates, and to obtain other results and advantages as may be brought out by the following description.

Referring to the accompanying drawings, in which like numerals of reference indicate the same parts throughout the several views,

Figure 1 is a top plan view of railway switch, showing the manner of applying my invention thereto;

Figure 2 is an enlarged transverse vertical sectional view through one side of the switch taken on line 2-2 of Fig. 1;

Figure 3 is a side elevation of the switch point shown in Fig. 2, the slide plates being shown in end elevation;

Figure 4 is a vertical longitudinal sectional view through a slide plate constructed in accordance with my invention, the electric heating coil being removed;

Figure 5 is a bottom plan view of the top plate of the slide plate having an electric heating coil mounted therein, the bottom insulating plate being removed;

Figure 6 is an enlarged transverse vertical sectional view taken on the line 6-6 of Fig. 4, showing the heating coil arranged between the main plate and top plate of the switch slide plate;

Figure 7 is a fragmentary plan view of a modified winding of the heating coil, and

Figure 8 is a transverse vertical sectional view taken on the line 8-8 of Fig. 7.

My invention is shown on the drawings as applied to the slide plates A of a conventional railway switch comprising the straight rail B, the turn-out rail C and the switch points D, all being mounted on the usual ties E.

A slide plate constructed in accordance with one form of my invention comprises a main plate 1 upon one end of which is adapted to be secured the main rail, and upon the other end of which is mounted the top or bearing plate 2 which is adapted to slidably receive the switch point. The underside of the top plate 2 is recessed at 3 to receive the electric heating coil embodying my invention, and is secured to the main plate 1 by means of the rivets 4, 5 and 6, a gasket 7 being interposed between the top plate 2 and the main plate 1 to prevent liquid from leaking into the recess 3. The top plate 2 and main plate 1 are further provided with openings 8 and 9 to receive a conventional spike or bolt for securing the slide plate to the railway tie.

My improved heated coil comprises a central insulating plate 10 which is recessed at one end thereof as at 11 to fit around the openings 8 and 9 through which the spike or bolt passes, and which is provided with a central longitudinal slot 12 enlarged inter-

mediate its ends as at 13 to clear the rivet 5. The resistance element is preferably formed of a single length of ribbon wire 14 coiled around the insulating plate 10 between the 5 side edges thereof and the edges of the slot 12 so as to form in effect a pair of parallel heating coils which are connected at one end thereof at 15 by a turn of wire which extends the full width of the plate 10. The ends 16 of 10 the coil are connected at 17 to the cables 18 which lead to the main line, the said cables entering the recess 3 through insulating bushings 19 fitted in grooves 20 and provided with transverse segmental ribs 21 fitting in correspondingly shaped recesses 22 formed in the top plate 2, the said insulating bushings preventing water or foreign matter from entering the recess 3, and the ribs 21 preventing the bushings from displacement. 15

20 The central insulating plate 10 and the heating coil are interposed between a pair of insulating plates 23 which serve to prevent contact of the coil with the main plate 1 and top plate 2, the said insulating plates 10 and 23 being rigidly secured to the top plate 2 by means of suitable bolts or rivets 24. The cables 18 are connected in any suitable manner to the main line wires 25 through which electric current can be supplied to 30 the various coils in the slide plates from any distance. I have found that with such a heating coil I can maintain a temperature of substantially 350° F. in the slide plates with a minimum consumption of current, 35 and the temperature in the various coils can be easily regulated by conventional means such as a rheostat.

The electric heating coil wound as shown in Figure 5 is particularly adapted for use 40 with direct current inasmuch as there is no reversal of current and hence no reactance developed by the coil. When alternating current is to be used the turn 15 of the coil is preferably passed from one side of the 45 plate 10 through an opening 26 in the plate to the opposite side thereof, as shown in Figures 7 and 8, thereby reversing the direction of the windings of the two sides of the coil. The magnetic fields set up by each 50 winding of each side of the coil, due to the alternating current, will then be in opposite directions, the resultant magnetic field of the entire coil being zero. Thus, no reactance will be developed by the coil. 55

With this construction it will be seen that the electric heating element is embodied directly in the slide plate, so that there is practically no waste of current in heating the ground adjacent the switch, the heat from 60 the slide plates being transmitted directly to the switch points so as to concentrate the heat at the point where it is most required to melt the snow and ice to maintain the switch in condition for proper operation. 65

To prevent the escape of the heat from the

slide plates through the ties and also to prevent the ties from becoming scorched or burned, I preferably provide a strip 27 of asbestos or other suitable material, between the main plate 1 and the respective tie. The 70 arrangement of the heating coil in the recess 3 between the main plate 1 and top plate 2 effectively protects the heating coil from injury from either the shocks incident to the use of the switch or the weather conditions, and also enables the application of the coil or the removal thereof from the slide plates to be made in a simple and quick manner, it being merely necessary to remove the rivets 4, 5 and 6 to detach the heating 75 coil from the slide plate. Thus the coils can be used interchangeably with numbers of slide plates, and the deterioration of the slide plates from wear does not impair the operation of or necessitate the discarding of 80 the heating coil.

While I have shown and described one embodiment of my invention, it will be understood that this is for the purpose of illustrating the principles thereof only, and that 90 many modifications and changes can be made in the detail construction thereof by those skilled in the art without departing from the spirit or scope of the invention. Therefore, I do not wish to be understood as 95 limiting myself except as required by the following claims when construed in the light of the prior art.

Having thus described the invention, what I claim is:

1. A slide plate for railway track switches including a body portion to support a switch point, and electrical heating means removably mounted in said body portion.

2. A slide plate for railway track switches 105 including a body portion to support a switch point and having a recess therein, an electrical heating element, and means for removably mounting said heating element in said recess.

3. A slide plate for railway track switches comprising a main plate, a bearing plate to support the switch point, and electrical heating means arranged between said main plate and said bearing plate.

4. In a slide plate for railway track switches, the combination of a main plate, a top plate secured to said main plate to support a switch point, said top plate being formed with a recess in the side thereof 110 adjacent said main plate, and an electric heating coil mounted in said recess.

5. In a slide plate for railway track switches, the combination of a main plate, a top plate secured to said main plate to support a switch point, said slide plate being formed with a recess between said main plate and said top plate, and an electric heating element mounted in said recess, said element comprising an insulating plate having 115

wire spirally wound around the same and other insulating plates arranged upon opposite sides of said heating element to insulate the same from said slide plate.

5 6. A slide plate for railway track switches including a main plate, a top plate secured to said main plate to support a switch point, said slide plate being formed with a recess between said main plate and said top plate

and a pair of openings extending outwardly 10 from said recess, an electrical heating element mounted within said recess and having its terminals projecting outwardly through said openings, and packing means for excluding foreign matter from said recess and 15 openings.

JOSEPH B. FEDER.
